US0D1087039S

(12) **United States Design Patent** (10) Patent No.: **US D1,087,039 S**
Bonow (45) Date of Patent: ** Aug. 5, 2025

(54) **DISPLAY PANEL WITH A GRAPHICAL USER INTERFACE**

(71) Applicant: **BELIMO HOLDING AG**, Hinwil (CH)

(72) Inventor: **Hendrik Bonow**, Zurich (CH)

(73) Assignee: **BELIMO HOLDING AG**, Hinwil (CH)

(**) Term: **15 Years**

(21) Appl. No.: **29/883,580**

(22) Filed: **Jan. 31, 2023**

Related U.S. Application Data

(62) Division of application No. 35/513,312, filed on Jul. 2, 2021 (U.S. filing date under 35 U.S.C. 384), and having an international filing date of Jul. 2, 2021, now Pat. No. Des. 996,989.

CLAIM

The ornamental design for a display panel with a graphical user interface as shown and described.

DESCRIPTION

The FIGURE is a front view of a display panel with a graphical user interface, showing the design.

The broken line in the FIGURE shows a display panel or portion thereof, and portions of the graphical user interface that form no part of the claimed design.

1 Claim, 1 Drawing Sheet
